UNITED STATES PATENT OFFICE.

GIANNI BETTINI, OF NEW YORK, N. Y.

MOTION-PICTURE APPARATUS.

Application filed March 6, 1925. Serial No. 13,604.

This invention is a novel motion picture apparatus, and generally speaking the principles involved are applicable either to an exposing apparatus or camera, or on the other hand to a projecting apparatus or lantern.

One of the main objects of the present invention is to afford a motion picture apparatus of such improved compactness, simplicity, convenience and inexpensiveness as to render it available for amateurs and home use. Further objects are to afford an apparatus of improved efficiency, accuracy and durability; especially with a spiral series of images upon a rotary disk record, and to improve the manner of actuating the disk record to rotate and progressively shift.

A special object is to provide automatic means to restore and reset a rotary disk projecting apparatus for restarting so that the picture series will be repeated again and again without the need of attention.

A further object is to provide for the automatic pause of the disk at a selected point, so as to afford still projection of an inscription, title, advertisement or other image, for substantial duration, without stoppage of the apparatus as a whole.

A further object is to provide a practical mechanism for projection of opaque motion pictures by reflected light.

Other advantages of the present invention will be elucidated in the hereinafter following description of one or more embodiments thereof or will be understood to those skilled in the subject. To the attainment of the recited objects and advantages the present invention consists in the novel motion picture apparatus and the novel features of combination, arrangement, operation, construction and detail herein shown or described.

In the accompanying drawings Fig. 1 may be considered a front elevation of a motion picture machine embodying the present invention, considering the front as the side toward which the images are projected; the picture disk or record being omitted, and part of the optical devices broken away, to better show the details of structure.

Fig. 1^a is a detached detail which should appear at the extreme left of Fig., but has been shown detached in order to avoid reducing the scale of the drawing to accommodate the entire front view on the sheet.

Fig. 2 is a rear elevation of the apparatus shown in Fig. 1, with certain parts broken out to show the structure of parts beyond, and this view indicating the image disk or record in projecting position.

Fig. 3 is a right elevation of the mechanism shown in Figs. 1 and 2, looking toward the right side of Fig. 1, with certain parts including the drive crank omitted.

Fig. 4 is a similar right elevation but taken partly in section on the line 4—4 of Fig. 1.

Fig. 5 is a plan view of a detail, taken substantially at the line 5—5 of Fig. 3.

Fig. 6 is a front elevation of the spring pressure device holding the record against the optical devices.

Fig. 7 is a left elevation of the apparatus shown in Figs. 1, 2, 3 and 4, taken partly in vertical section on the line 7—7 of Fig. 1.

Fig. 8 shows a modified embodiment, and may be considered as either a plan view or an elevation of certain parts.

Fig. 9 is a partial front view of certain parts shown in Fig. 8.

The machine is shown as having a base plate 10 which supports the several mechanisms and which itself may be shiftable angularly and otherwise, and tiltable, in order to direct the mechanism properly towards the subject or curtain. Upstanding from the base 10 is shown a main frame wall 11, giving support to much of the mechanism, and at the right end, is a rigid bracket 12 extending upwardly to where it gives support to certain of the mechanism. Spaced away from the main wall 11 is a rear wall or plate 13, shown partly broken away in Fig. 2, and held in rigid relation to the remainder of the frame by means of posts 14 extending between the main wall and the plate 13.

The record or image carrier 15 is shown as a large circular disk, which may be transparent for the purpose of projection through the record, although as in Figs. 8 and 9 it may be opaque. The image record 15 may be either a sensitive plate upon which images are to be exposed and developed, or a developed and printed record suitable for projection. In either case there will be a succession or series of image spaces 16, arranged substantially as partially shown in Fig. 2, the image 16^a being the first of the series and the succeeding ones trending

peripherally around the disk and gradually inward in a spiral manner toward the center; so that the entire disk is substantially covered with small images in spiral series.

5 In the preferred form or embodiment the feeding or intermittent advance of the disk from one image space to the next alongside in the spiral picture series is effected by means of successive perforations 17, either 10 in the body of the disk itself as in Fig. 2 or in an adjacent plate as in Fig. 9, the perforations adapted to cooperate with a four motion feed device or finger as will be described. The disk may have a central 15 aperture at the point 18 in Fig. 3 and a second aperture at the point 19 spaced from the center for the purpose of insuring accurate positioning of the record in the machine. It is to be understood that the record may be 20 removed or inserted, and when inserted may be progressively operated to project the entire series of images to produce motion pictures, and that any record may be replaced with any other record at will.

25 When the record 15 is introduced into the machine it may be engaged and supported substantially as follows. A metal supporting disk 21 is shown, secured upon a short rotary shaft 22 and having a positioning 30 pin 23. The disk central aperture 18 engages over the shaft 22 and the aperture 19 engages over the positioning pin 23, thereby accurately determining the position of the record disk in the machine. When the record 35 is thus applied to the supporting disk it may be held by a spring clamp device 25 of spider form, seen in Figs. 1, 3, and 4, the bent arms applying pressure to hold parts of the record firmly against the rotary support. The clamp device 25 may be manipulated by its knob or handle 26. One of the 40 bent arms is formed with a notch 27 to engage a pin 23, thereby properly positioning the clamp. A spring catch 28 is mounted in 45 the knob 26 in a manner to engage a slot in the shaft 22, thus latching the clamp in place. To remove the image record it is only necessary to press the spring catch 28 and remove the spider clamp 25, upon which 50 the record may be detached.

As already indicated the image record is to be not only rotatable to bring successive peripheral portions to the optical position, but is to be shifted, or moved bodily transversely of its axis in a lateral or horizontal manner so as to give the progressive advance necessary to correspond with the spiral arrangement of the images. For the 55 purpose of lateral movements the rotary shaft 22 which carries the holding disk 21 and record 15 may be journalled in a block or carriage 30 which is fitted snugly in a horizontal slot 31 formed in the frame wall 11, the carriage having its flanges embracing 60 the opposite sides of the wall, giving steadi-

ness, while permitting the carriage to slide horizontally for a distance equal substantially to the effective radius of the picture disk. The disk thereby is so mounted that it may be rotated, and also bodily shifted 70 transversely of its axis of rotation, so as to bring all portions of its surface in line with the optical axis.

One preferred feature of this invention is that the horizontal or progressive shifting movement of the disk and carriage shall be effected, not directly from the drive mechanism, but from the rotation of the disk itself. This insures proper coordination in the rotary and sliding movements. There 75 is shown a horizontal feed screw or worm 34, having a pitch corresponding to the pitch of the convolutions of the image spiral and adapted to shift the carriage and the disk mounted thereon. This feed worm 34 passes 80 through and is journalled in the rear flange 32 of the carriage 30. A member or arm 33, later to be referred to, engaged on the worm outside the flange, effects axial movement of the worm 34 in one direction, as fully described below. The worm however may rotate in the flange 32, and at its left or interior end is provided with a bevel gear 35 engaging a corresponding bevel gear on the disk shaft 22. By this arrangement one complete rotation of the disk and shaft 22 produces one complete rotation of the worm 34. The right or outer end of the worm is arranged to slide and rotate freely within a bearing block 36 secured at the upper end of the fixed frame standard 12, and the outer extremity of the worm is shown provided with a knurled head 37 to facilitate manipulation. Instead of engaging in the interior threads of a nut the feed worm 34 is shown 95 as engaged by a single pin or follower 38, which is normally fixed in position, so that the rotation of the disk and worm effects 100 synchronic and corresponding horizontal shifting thereof, the worm shifting, or translating, axially, responsive to the drive power of gear 35, giving a resultant spiral, and serving to bring the entire series of image spaces successively to the optical position. When the follower 38 is disengaged from the 105 worm, said worm may be axially shifted by hand without rotation.

Coming to the optical part of the apparatus, the frame wall 11 is shown formed with a circular hole 40 through which projection takes place. In front of the wall opening 40 is the objective lens 42, which may be of usual type, having a focusing sleeve 43. A screw device 44 operates to 110 adjust the lens vertically to adapt it to the position of the images on the record disk. These elements may be mounted bodily upon a swinging arm 45 which is pivoted at its lower end at 46 so as to swing forwardly 115 and down in order to give access for in- 120

125 130

serting and removing records. The upper end of the swinging post or arm 45 is enlarged into the form of a light shield 47, centrally carrying the objective lens. 5 When these parts are in normal position as seen in Figs. 1 and 7 they are held latched there by a spring latch device 48. Mounted at the rear end of the objective lens tube is shown a conical extension or tube 49, 10 the rear or interior end of which is formed with a square window 50 corresponding in size and position with the successive images. This window is adjusted upwardly and downwardly together with the objective lens by the screw 44. In Fig. 7 the picture disk 15 is shown as contacting snugly against the window tube 49. It is desirable to have a resilient pressure holding the disk forwardly against the window 15, 20 and for this purpose a bent spring 52 is shown, having a cut away area or window 53, as seen separately in Fig. 6, the spring being secured to the frame wall 11 by screws 54. The spring presser plate 52 is 25 so formed that it may be pulled backward and thus slightly retracted from the picture disk, so as to relieve the pressure and permit free rotation of the disk without scraping contact and possible injury, when 30 desired. For the purpose of so retracting the spring presser a headed pin 55 is shown passing through the frame wall 11 and adapted both to slide and rotate. The rear end of the pin 55 has a lateral arm or 35 rocker 56, which may be moved by hand to retract the presser. This may conveniently be done through a fixed sleeve cam 57 mounted on the frame wall, its rear or cam surface being so formed that when 40 the rock arm 56 is swung over to the left, toward the observer in Fig. 7, the arm and therefore the pin 55 are cammed rearwardly, so that the head of the pin forces the presser away from the picture disk. 45 Later will be explained how the rock arm 56 may be automatically actuated at certain times.

To the rear of the objective lens, picture disk, and the frame wall window 40 is 50 shown a condenser lens 60, and to the rear of this is a source of illumination, which may be an encased electric lamp 62. This may be rendered adjustable to the axis of projection by having a downward stem 63 55 passing through a carriage 64. The lamp may be raised, lowered and swung, and when in position may be fixed by set screw 65. The carriage may be mounted to slide forwardly and rearwardly on fixed guide rods 66. The lamp case 62 may enclose a condensing lens cooperating with the other lenses, and no claim is made to any novelty in the lens system herein indicated. 60 This completes the description of the optical part of the apparatus, with the exception

of the shutter, to be described in connection with the driving and disk feeding mechanisms.

The driving and peripheral feed mechanism may be as follows. A drive shaft 70 is indicated carrying a crank 71 so that muscular power can be applied to the machine, all the movements taking their actuation from this source. Instead of a crank an electric drive may be used, a motor 75 being geared down to give a rotary speed resulting in 16 exposures per second more or less. The drive shaft 70 is shown as passing through an elongated bearing 72 at the rear side of the frame plate 13. At 80 its inner extremity the shaft carries a spur gear 73 and in front of that a bevel gear 74 adapted to drive the second shifter, or resetting shaft 100 hereafter to be described. The spur gear 73 is shown in mesh with a 85 pinion 75 on a short countershaft which also carries a gear 76 engaging in turn a pinion 77 on the main shaft 78, so-called because this shaft carries the shutter and the control means for the picture disk feed. 90 The described gearing will be seen to give multiplied motion so that a slow steady turn of the crank gives the necessary speed of rotation of the main or cam shaft 78, which makes one revolution for each advancing step of the picture disk. 95

A shutter 80 is shown attached to the main shaft 78, the same consisting of three wings in balanced arrangement, one of the wings serving to obstruct the light path during each feed movement of the picture disk, projection taking place through the spaces between the three wings. The shutter also has substantial thickness and weight so as to serve as a steadyng fly wheel. 100

Referring to Fig. 7 and others the main shaft 78 is seen to carry two cams 82 and 83, the cam 82 serving to vibrate upwardly and downwardly the feed carriage to be described, and the cam 83 serving to advance the feed member into contact with the picture record, and retract it. The feed member being mounted on the vibrating carriage thus receives four motions namely up, forward to engage the record, downward to advance the record, and rearward to disengage the record. The cam 82 is in the nature of an eccentric, but is shaped as indicated in Fig. 2 to give a quick feeding movement, with a pause, and a smooth return 115 movement. The cam 83 is not fixed to the cam shaft but is axially movable and capable of sliding forwardly and rearwardly, guided and limited by a key slot and pin device, a spring 84 pressing the cam forwardly to its normal position, as shown in Fig. 7, the purpose of the spring being to permit yield of the cam, so that it can be displaced or forced backwardly, as will be explained, to prevent its moving the feed 120 125 130

member into operative feed engagement with the picture disk at certain times.

The four motion feed device may consist of a feed point or pin 86 adapted to enter and engage the successive feed apertures 17 in the picture disk. The feed point is mounted at the upper end of a light resilient body or spring finger 87 which in turn is given reciprocal feed movement longitudinally of the finger and up and down by the carriage yet to be described. The lower end of the feed finger is pivoted at 88 upon an extension of the carriage for reciprocal movement transversely of the disk, and a spring 89 surrounds the pivot pin, operating always to press the feed finger rearwardly, in a direction away from engagement with the picture disk. The finger cam 83 being an open cam, pressing forwardly on the feed finger at certain times, the spring 89 acts to hold the finger pressed rearwardly into engagement with the cam. The feed finger and feed point may be adjusted laterally so as exactly operatively to register with the feed apertures, for example by means of a slot 90 formed in the feed finger, engaged by a guide pin 91, mounted on a slide bar 92, seen at the left part of Fig. 1, the extremity of the bar being seen in Fig. 1A, where an adjusting device, consisting of a thumb screw 93, is arranged to shift the bar minutely and thus adjust the feed device laterally to the feed perforations.

The feed finger is carried on a vibrating carriage 85 moved upwardly and downwardly so as to reciprocate alongside the disk by the cam 82. The vertical side edges of the carriage are guided in vertical guides 96, and the rear side of the carriage is provided with flanges 97 respectively overlying and underlying the carriage vibrating cam 82. The carriage and connected parts are shown arranged somewhat below the optical axis, as seen in Figs. 1 and 2, and as the feed finger operates at a point somewhat lower than the center of the picture disk the carriage and guides are arranged at a slight incline from the vertical, so that the feed finger movements will be tangent to the line of perforations. An important structural feature is the relative arrangement of the parts as described and shown, the carriage 85 being formed with an opening or slot 98 through which the main shaft 78 extends, so that the two cams 82 and 83 can be arranged in close proximity to the carriage and feed finger, and yet driven from a point to the rear.

The mechanism so far described is sufficient and complete for hand operation. The turning of the crank puts the entire series of pictures through successive exposures. When the end of the series is reached the feed ceases because there are no further perforations 17 to be engaged by the feed

finger. The operator can thereupon restore the parts and proceed again with the same or a new record. A quick restoration of the parts may be effected by retracting the follower pin 38 from the feed worm 34 and moving the carriage 30 back to the starting position by pulling outwardly on the thumb nut 37 at the extremity of the feed worm. Upon reengagement of the follower and worm operations can be repeated.

A quick return or resetting mechanism operated by the crank or drive shaft may be as follows. The second shifter, or resetting worm shaft 100 is shown as axially stationary and having bearings in the frame parts 12 and 13. This is beneath and somewhat to the front of the main worm 34. It has a bevel gear 101 engaging the bevel gear 74 on the drive shaft, and the worm shaft 100 could be employed as the drive shaft if desired. The grooves of the return worm 100 are cut in the same manner as the main worm, but the follower instead of the worm shifts, giving therefore a rapid reverse feed motion, which may be transmitted as follows to the carriage 30 and the spiral playing record. A follower pin 103 is arranged to engage the grooves of the worm 100, this follower being mounted on a rock arm 104, which is shown secured to a collar 105, having a pin or spline 106 engaging the longitudinal groove or slot 107 in a rock shaft 108. The collar and rock arm thereby may slide along the grooved shaft, but are compelled to rock with the shaft. The collar 100 also have a groove and yoke connection with the plate or arm 33 already referred to, which is yoked at its upper end and straddles the worm 34 adjacent to the flange 32 of the carriage 30, so that the carriage, the plate 33, the collar 105 and the rock arm 104 are compelled to travel longitudinally as a unit. The rock shaft 108 at its right hand or outer end has attached to it a second rock arm 109 which carries the follower 38 engaging the main worm 34. Incidentally the rock arm 109 has a plate cam 110 at its top end, shown separately in Fig. 5, for a purpose to be described.

By this arrangement the feed follower 38 and the return follower 103 are interconnected, through the rock shaft 108, so that one or the other, but not both of them, will be engaged with the respective worms, engagement with one alternating with that of the other. Also it will be perceived that follower parts of the shifting mechanism control with which shifter the shifting is to be effected. By this arrangement when a record has been completely exposed the shaft 108 and the two rock arms may be rocked, thus rendering the main worm inoperative and engaging the return worm, which therefore operates at high speed to move the collar 105 the worm 34, and the

carriage 30 back to initial position. A device is shown to prevent breakage and cause disengagement of the return worm at the end of the return movement, consisting of a 5 cam finger or follower-actuator 112 mounted rigidly on the worm shaft 100, in a position to strike and swing outwardly the rock arm 104, and thereby disengage the follower. Upon this occurrence the main follower 38 10 may be reengaged with the main worm and operations repeated.

In order to insure the engagement of one or the other of the followers with their respective worms a spring arrangement 113 15 may be employed, such as best illustrated in Fig. 3, this spring being attached to the lever 109, and arranged to pull it toward a point below its fulcrum shaft 108, so that in either position the spring tends to throw the lever 20 away from a mid position. Thus in full lines the spring is tending to engage follower 38 with the worm 34; while in dotted lines it is pulling reversely to engage follower 103 with the worm 100.

25 The entire mechanism may be coordinated to cause successive repeated operations of the same picture disk wholly automatically and without any attention from the operator. For this purpose the control may come from 30 a slow moving controller, or cam wheel 115, fulcrumed on a bracket 116 attached to the standard 12. The periphery of the cam wheel 115 is formed with gear teeth 117 which are engaged by a worm 118 formed at the 35 extremity of the worm shaft 100. The size and number of teeth of the cam wheel are such that the wheel would make exactly one complete rotation with each complete cycle of operation. One function of the control 40 cam 115 is to shift from slow forward feed to quick return feed of the picture disk, and this is shown as herein performed through a cam or block 119, on the periphery of the wheel, arranged to strike a pin 120 at the 45 lower end of a lever arm 121 which is fulcrumed at 122 on a fixed bracket 123, and has an upward extension 124 cooperating with the plate cam 110 on the follower arm 109 already referred to. As shown in Fig. 2 50 the cam block 119 has not yet reached engaging position, but when it does so it will press upon the pin 120, swinging the lever 121 against the resistance of spring 125, while the upper lever arm 124 moves in- 55 wardly against cam 110, as seen in plan view in Fig. 5. The control cam in this way causes the camming forward of the rock arm 109, and when it passes its mid position the spring 113 will cause the arm to snap 60 away, the rock shaft 108 operating to snap the other rock arm 104 to carry the follower 103 into engagement with the return worm 100. When the cam block 119 has passed the pin 120 it releases it, to return to the normal 65 position shown in Fig. 2.

By this arrangement, when the picture series has been completely exposed the control cam causes the drive to shift from the worm 34 to the worm 100, resulting in a rapid shifting back to starting position of 70 the carriage 30, worm 34, and playing record. At the end of the return movement the finger 112 operates as described to disengage follower 103, and the spring 113 causes the feed follower 38 to snap back into engagement with the feed worm, thus causing repetition of actions.

An auxiliary connection serving to remove the pressure and friction on the picture disk during the rapid return movement 80 may be as follows. The upper end of the lever arm 124, controlled by the cam wheel 115, has a long link connection 127 to the rock arm 56 already referred to, connected with the pin 55, the head of which overlies 85 the spring presser 52. In this way the pressure is removed from the disk until the control cam permits the parts to resume normal position just prior to the restarting of the record. 90

Another function of the control cam is to render the peripheral feed mechanism inoperative during certain predetermined periods, while the rest of the mechanism continues acting. This is preferably done by 95 preventing the feed finger 86 from engaging operatively with the picture record, namely by forcing the feed finger cam 83 rearwardly so that it will not operate to move the finger into engagement with the record, 100 the locus of the path of the feed finger being thus altered. As already explained the cam is arranged to yield resiliently for this purpose. This effect may be secured through a forked lever 130 which straddles the cam 105 shaft 78 and is arranged to press back upon the forward side of the hub of the cam 83. The forked lever is fulcrumed at 131 and has a downward extension 132 adapted to be thrown forwardly by a trip or cam 133. 110 The cam 133 has a bevel face arranged to press forwardly the lever arm 132, and is fulcrumed at 134. The cam may be actuated through a long link 135, see Figs. 2 and 7, 115 extending across the machine, the far end supported by an arm 136, with a spring 137 pulling on the arm 136 and tending to hold the cam 133 inoperative. The arm 136 has a cam pin 138 adapted to be contacted and thrust by an elongated additional cam block 120 139 on the cam wheel 115. When the cam block strikes the pin 138 this throws the trip 133 and represses the feed finger cam 83, so as to suspend the peripheral feed or 125 intermittent rotary motion, and thereby the horizontal feed motion of the picture disk. During the suspension of feed movements the remainder of the operations continues; the shutter continues to spin, the cam wheel 115 continues its slow rotation, etc. The re- 130

sult is that there will be, during the suspension, the still projection of the image in front of the optical window. This scheme is of value in order to hold a title or inscription in position for any given length of time before resuming the projection of pictures. It will be understood that the total periphery of the control cam, with the feed suspensions referred to, shall be such that the actual feed of the record will be such as is necessary to carry it through from the initial to the final image. As herein shown the cam block 139 is so arranged as to suspend the feed at the final image, and again, after resetting, at the initial image.

When the cam block 139 reaches the pin 138 it will throw the feed mechanism into inoperative condition, so that the final image will be projected as a still picture. At this time the feed block 119 has not yet contacted the pin 120. When it does contact the pin so as to throw the lever 124 this will effect the snapping of the combined lever 109, 104, disengaging the follower 38 and engaging the return follower 103 with the fast turning worm 100. The disk will thereby be reset, as described, and the finger 112 will restore the followers to initial position. Thereupon the first image will be projected upon the curtain as a still picture, the feed still being suspended. When the cam block 139 completely passes by the pin 138 the feed parts are restored to operative condition and normal motion picture operation commences, and continues until the entire series of pictures has been exposed.

In Figs. 8 and 9 is shown a modification wherein the images are carried on an unperforated opaque picture disk 15^a which may be a photographic reproduction on paper from the image negative. This disk has central aperture 18 and positioning hole 19, as in the main embodiment, and when in position lies flatly against a perforated disk 15^b which may be of aluminum, cardboard or other light material, the perforations 17^b cooperating with the feed mechanism already described. A lamp 62^a is arranged to illuminate intensely the image 16^b which lies in the optical axis, and the objective 42^b projects the image upon the curtain. This embodiment is particularly adapted for home use, is more safe against conflagration, and enables a cheaper image disk to be provided; although the distance of projection will not be so great as with the main embodiment.

It will thus be seen that there has been described a motion picture apparatus, available in some features either for a camera or for projecting purposes, and in other features for projecting purposes, the same embodying the principles and attaining the objects hereinbefore recited. Since many

matters of combination, arrangement, construction and design may be variously modified without departing from the principles of the invention it is not intended to limit the same to such matters except so far as set forth in the appended claims.

What is claimed is:

1. Moving picture apparatus using a bodily shiftable disk picture record including, in combination, two disk shifter members, means adapted to connect said disk for being shifted by either of said members, one of said members being shiftable to shift said disk, and means adapted to shift said shiftable member by actuation of the other shifter member.

2. Moving picture apparatus using a rotary disk picture record, the axis of which is transversely shiftable, including, in combination, two disk shifter members, means adapted to connect said disk for being shifted by either of said members, one of said members being shiftable to shift said disk, and means adapted to shift said shiftable member by rotation of said disk.

3. Moving picture apparatus using a rotary disk picture record, the axis of which is transversely shiftable, including, in combination, two disk shifter members, means adapted to connect said disk for being shifted by either of said members, one of said members being shiftable to shift said disk, and means adapted to shift said shiftable member by rotation of said disk, and means adapted to shift said shiftable member by actuation of the other shifter member.

4. Moving picture apparatus using a rotary disk picture record, the axis of which is transversely shiftable, including, in combination, means including a member engaging said disk at successively different points to effect intermittent rotation thereof, a gear driven by rotation of said disk, and a disk shifter translatable to shift said disk and translated by power from said gear.

5. Moving picture apparatus using a rotary disk picture record, the axis of which is transversely shiftable, including, in combination, a gear driven by rotation of said disk, a disk shifter translatable to shift said disk and translated by power from said gear, and mechanism operated automatically at a predetermined point in a cycle of operations of said apparatus to render said power ineffective to translate said shifter.

6. Moving picture apparatus using a rotary disk picture record having feed apertures, the axis of which is transversely shiftable, including, in combination, a gear driven by rotation of said disk, a disk shifter translatable to shift said disk and translated by power from said gear, and a feed finger reciprocally movable to engage suc-

cessive feed apertures in said disk to rotate said disk.

7. Moving picture apparatus using a rotary disk picture record, the axis of which is 5 transversely shiftable, including, in combination, a gear driven by rotation of said disk, a disk shifter translatable to shift said disk and translated by power from said gear, a feed finger reciprocally movable to engage 10 successive feed apertures in said disk to rotate said disk, and means adapted to arrest normal feed rotation of said disk by said finger.

8. Moving picture apparatus using a rotary disk picture record, the axis of which is 15 transversely shiftable, including, in combination, a gear driven by rotation of said disk, and a disk shifter translatable to shift said disk and translated by power from said 20 gear, and mechanism operated automatically at a predetermined point in a cycle of operations of said apparatus to arrest normal feed rotation of said disk.

9. Moving picture apparatus using a rotary disk picture record, the axis of which is 25 transversely shiftable, including, in combination, an axially shiftable worm, a follower engageable and disengageable with said worm, a picture record supporting carriage shiftable with said worm, means 30 adapted to rotate said worm, and automatic mechanism for effecting engagement and disengagement of said follower and said worm.

35 10. Moving picture apparatus using a rotary disk picture record, the axis of which is transversely shiftable, including, in combination, an axially shiftable worm, a follower for said worm, a picture record supporting carriage shiftable with said worm, means 40 adapted to rotate said worm, a second worm, a follower for the latter worm, and a follower actuator rotatable with the latter worm.

45 11. Moving picture apparatus using a rotary disk picture record including, in combination, a finger having reciprocal disk-feeding movement and reciprocal disk engaging and disengaging movement, and 50 means adapted to effect said movements, including a rotatable cam adapted to effect said disk-engaging movement, said cam being shiftable to inoperative position to fail to cause feed engagement of said finger with 55 said disk, and means for shifting said cam to inoperative position at intervals.

12. Moving picture apparatus using a rotary disk picture record including, in combination, a finger having reciprocal disk- 60 feeding movement and reciprocal disk engaging and disengaging movement, a feed carriage on which said finger is pivoted for disk engaging and disengaging movement, a driven shaft having a cam for reciprocating 65 said feed carriage to effect disk-feeding

movement of said finger, and a second cam axially movable on said shaft and adapted to effect disk engaging movement of said finger, and means adapted yieldingly to hold said second cam in axial position on said 70 shaft to cause said finger to effect feed engagement with said disk as it reciprocates.

13. Moving picture apparatus using a rotary disk picture record including, in combination, a finger having reciprocal disk-feeding movement and reciprocal disk engaging and disengaging movement, a feed carriage on which said finger is pivoted for disk engaging and disengaging movement, a driven shaft having a cam for reciprocating 80 said feed carriage to effect disk-feeding movement of said finger, and a second cam axially movable on said shaft and adapted to effect disk engaging movement of said finger, and means adapted yieldingly to hold 85 said second cam in axial position on said shaft to cause said finger to effect feed engagement with said disk as it reciprocates, and a lever actuated in timed relation with operation of the apparatus adapted to displace said cam axially of said shaft to position where it fails to cause feed engagement of said finger with said disk as the finger reciprocates.

14. Moving picture apparatus using a rotary disk picture record including, in combination, a finger having reciprocal disk-feeding movement and reciprocal disk engaging and disengaging movement, a driven shaft having a cam rotatable therewith, a feed carriage having flanges engaging said cam adapted to be reciprocated by said cam, 95 said finger being connected to said carriage to receive said disk-feeding movement, and a second cam axially movable on said shaft 100 and rotatable with said shaft, and disposed to effect feed-engaging movement of said finger.

15. Moving picture apparatus using a rotary disk picture record including, in combination, a finger having reciprocal disk-feeding movement and reciprocal disk engaging and disengaging movement, a driven shaft having a cam rotatable therewith, a feed carriage having flanges engaging said 110 cam adapted to be reciprocated by said cam, said finger being connected to said carriage to receive said disk-feeding movement, and a second cam axially movable on said shaft and rotatable with said shaft, and disposed to effect feed-engaging movement of 115 said finger, and a spring adapted to press said finger into engagement with said cam.

16. Moving picture apparatus using a rotary disk picture record including, in combination, a finger having reciprocal disk-feeding movement and reciprocal disk engaging and disengaging movement, a driven shaft having a cam rotatable therewith, a feed carriage having flanges engaging said cam 125 130

adapted to be reciprocated by said cam, said finger being connected to said carriage to receive said disk-feeding movement, and a second cam axially movable on said shaft

5 and rotatable with said shaft, and disposed to effect feed-engaging movement of said finger, and a spring adapted to press said finger into engagement with said cam, and a spring on said shaft adapted to resist axial 10 displacement of said second cam away from said disk.

17. Moving picture apparatus using a rotary disk picture record including, in combination, a finger having reciprocal disk-feeding movement and reciprocal disk-engaging and disengaging movement, a driven shaft having a cam rotatable therewith, a feed carriage having flanges engaging said cam adapted to be reciprocated by said cam, 20 said finger being connected to said carriage to receive said disk-feeding movement, and a second cam axially movable on said shaft and rotatable with said shaft, and disposed to effect feed-engaging movement of said finger, 25 said finger comprising a resilient body having a perforation engaging pin.

18. An apparatus of the character described including, in combination, a picture record supporting carriage, a worm automatically axially shiftable in one direction during picture taking or projection, said carriage being connected to be shifted by axial shift of said worm, a second worm, connections whereby said second worm may be 30 operatively connected to shift the other worm axially in the opposite direction, a driving shaft, and means adapted to be operatively connected to rotate said worms from said shaft, said second worm much faster than the 40 other worm.

19. An apparatus of the character described including, in combination, a picture record supporting carriage, a worm automatically axially shiftable in one direction 45 during picture taking or projection, said carriage being connected to be shifted by axial shift of said worm, a second worm, connections whereby said second worm may be operatively connected to shift the other worm 50 axially in the opposite direction, a driving shift, and means adapted to be operatively connected to rotate said worms from said shaft, said second worm much faster than the other worm, said last mentioned means 55 including a rotative picture record operatively connected by its rotation to rotate said axially shiftable worm.

20. Moving picture apparatus using a progressively movable picture-series record 60 including, in combination, a finger having reciprocal record-feeding movement and reciprocal record engaging and disengaging movement, a driven rotatable cam adapted to effect said record engaging movement, a controller driven by operation of the ap-

paratus, and devices adapted to be actuated by said controller to shift said cam to position to fail to cause feed engagement of said finger with said record.

21. Moving picture apparatus using a progressively movable picture-series record including, in combination, a finger having reciprocal record-feeding movement and reciprocal record engaging and disengaging movement, a driven rotatable cam adapted 70 to effect said record engaging movement, a controller driven by operation of the apparatus, and devices adapted to be actuated by said controller to shift said cam to position to fail to cause feed engagement of 75 said finger with said record, said devices including a lever reciprocal transversely of its axis, and a trip movable by said controller into and out of position to cause pivotal movement of said lever to effect said 80 shift.

22. Moving picture apparatus using a progressively movable picture-series record including, in combination, a finger having reciprocal record-feeding movement and reciprocal record engaging and disengaging movement, a driven rotatable cam adapted 90 to effect said record engaging movement, a controller driven by operation of the apparatus, and devices adapted to be actuated by said controller to shift said cam to position to fail to cause feed engagement of 95 said finger with said record, said cam being reciprocal in one direction with said finger.

23. Moving picture apparatus using a progressively movable picture-series record including, in combination, means adapted to feed said record in a manner to exhibit an animated picture, including a record feeding worm, a second worm, worm followers, one for each worm, a rock shaft for moving said followers into and out of engagement with their respective worms, a cam movable with said shaft, a lever, a controller driven 100 in an endless path by operation of the apparatus, adapted to actuate said lever to actuate said cam to rock said shaft in one direction, and a cam finger rotatable with one of 110 said worms adapted to rock said shaft in the 115 opposite direction.

24. Moving picture apparatus using a progressively movable picture-series record including, in combination, means adapted to feed said record in a manner to exhibit an animated picture, including a record feeding worm, a second worm, worm followers, one for each worm, a rock shaft for moving said followers into and out of engagement with their respective worms, a cam movable with 120 said shaft, a lever, a controller driven in an endless path by operation of the apparatus, adapted to actuate said lever to actuate said cam to rock said shaft in one direction, and a cam finger rotatable with one of 125 said worms 130

worms adapted to rock said shaft in the opposite direction, a spring adapted to press said record at the optical axis of the apparatus, and connections whereby pressure of 5 said spring is varied dependent on which of said followers is in worm engagement.

25. Moving picture apparatus using a rotary disk picture record including, in combination, a frame, a carriage reciprocally 10 slidable on said frame, a shaft rotatable on said carriage having a gear, an axially reciprocal worm with which said carriage is reciprocal, a worm follower movably mounted on said frame for engagement and disengagement 15 with said worm, a feed carriage reciprocal alongside said disk having a disk feeding finger pivoted thereon for movement to and from the disk, a drive shaft having a cam for reciprocating said carriage, and a 20 second cam axially movable on said driving shaft and spring pressed toward said disk, adapted to move said finger toward said disk.

26. Moving picture apparatus using a rotary disk picture record including, in combination, a frame, a carriage reciprocally 25 slidable on said frame, a shaft rotatable on said carriage having a gear, an axially reciprocal worm with which said carriage is reciprocal, a worm follower movably mounted on said frame for engagement and disengagement 30 with said worm, a feed carriage reciprocal alongside said disk having a disk feeding finger pivoted thereon for movement to and from the disk, a drive shaft having a cam for reciprocating said carriage, and a second cam axially movable on said driving 35 shaft and spring pressed toward said disk, adapted to move said finger toward said disk, an axially stationary worm, means adapted simultaneously to rotate said drive 40 shaft and said axially stationary worm, and a worm follower reciprocal with said first mentioned carriage and movable into and 45 out of engagement with said axially stationary worm.

27. Moving picture apparatus using a rotary disk picture record including, in combination, a frame, a carriage reciprocally 50 slidable on said frame, a shaft rotatable on said carriage having a gear, an axially reciprocal worm with which said carriage is reciprocal, a worm follower movably mounted on said frame for engagement and disengagement 55 with said worm, a feed carriage reciprocal alongside said disk having a disk feeding finger pivoted thereon for movement to and from the disk, a drive shaft having a cam for reciprocating said carriage, and a 60 second cam axially movable on said driving shaft and spring pressed toward said disk, adapted to move said finger toward said disk, an axially stationary worm, means adapted simultaneously to rotate said drive 65 shaft and said axially stationary worm, and

a worm follower reciprocal with said first mentioned carriage and movable into and out of engagement with said axially stationary worm, a control wheel driven from said last mentioned worm, a control block 70 on said wheel, a lever in the path of said block, and means whereby actuation of said lever by said block shifts one of said followers out of engagement with its worm and the other into engagement with its worm, 75 and means adapted automatically to reverse said shift at intervals.

28. Moving picture apparatus using a rotary disk picture record including, in combination, a frame, a carriage reciprocally 80 slidable on said frame, a shaft rotatable on said carriage having a gear, an axially reciprocal worm with which said carriage is reciprocal, a worm follower movably mounted on said frame for engagement and disengagement 85 with said worm, a feed carriage reciprocal alongside said disk having a disk feeding finger pivoted thereon for movement to and from the disk, a drive shaft having a cam for reciprocating said carriage, and a 90 second cam axially movable on said driving shaft and spring pressed toward said disk, adapted to move said finger toward said disk, an axially stationary worm, means adapted simultaneously to rotate said drive 95 shaft and said axially stationary worm, and a worm follower reciprocal with said first mentioned carriage and movable into and out of engagement with said axially stationary worm, a control wheel driven from said last mentioned worm, a control block on said wheel, a lever in the path of said block, and means whereby actuation of said lever by said block shifts one of said followers out of engagement with its worm and the other into engagement with its worm, 100 means adapted automatically to reverse said shift at intervals, an additional block on said wheel, and means controlled by said additional block for at intervals, cutting out operative feed engagement of said finger with said disk.

29. Moving picture apparatus using a rotary disk picture record, the axis of which is transversely shiftable, including, in combination, a finger having reciprocal disk-feeding movement and reciprocal disk-engaging and disengaging movement, a rotatable cam adapted to effect said disk engaging movement, said cam being shiftable to position to 115 fail to cause feed engagement of said finger with said disk, a gear driven by said disk and shiftable therewith, and a disk shifter driven by said gear to shift said disk.

30. Moving picture apparatus using a rotary disk picture record, the axis of which is transversely shiftable, including, in combination, a finger having reciprocal disk-feeding movement and reciprocal disk-engaging and disengaging movement, a rotatable cam 120 125 shiftable therewith, and a disk shifter driven by said gear to shift said disk.

130

- adapted to effect said disk engaging movement, said cam being shiftable to position to fail to cause feed engagement of said finger with said disk, a gear driven by said disk and shiftable therewith, a disk supporting carriage, a worm automatically axially shiftable in one direction during picture taking or projection and driven by said gear, said carriage being connected to be shifted by 5 axial shift of said worm so as to shift said disk, a second worm, means adapted operatively to connect said second worm with the other worm to shift the latter in the opposite direction, a driving shaft, and means 10 adapted to be operatively connected to rotate said worms from said driving shaft, said second worm much faster than the other.
31. Moving picture apparatus using a rotary disk picture record, the axis of which is transversely shiftable, including, in combination, a finger having reciprocal disk-feeding movement and reciprocal disk-engaging and disengaging movement, a rotatable cam adapted to effect said disk engaging movement, said cam being shiftable to position to fail to cause feed engagement of said finger with said disk, a gear driven by said disk and shiftable therewith, a disk 15 supporting carriage, a worm automatically axially shiftable in one direction during picture taking or projection and driven by said gear, said carriage being connected to be shifted by axial shift of said worm so as to shift said disk, a second worm, means adapted operatively to connect said second worm with the other worm to shift the latter in the opposite direction, a driving shaft, means 20 adapted to be operatively connected to rotate said worms from said driving shaft, said second worm much faster than the other, a window frame at the optical axis of the apparatus, means adapted resiliently to press said disk against said window frame, and means adapted automatically to relieve said pressure at intervals.
32. Moving picture apparatus using a rotary disk picture record, the axis of which is transversely shiftable including, in combination, means adapted to feed said disk and shift it in one direction to exhibit an animated picture, means adapted to shift said disk in the opposite direction at increased speed to reset the disk for repetition, a plate 25 adapted resiliently to press on the disk adjacent the optical axis, and means timed in its operation to relieve said pressure during resetting movement of said disk.
33. Moving picture apparatus using a rotary disk picture record, the axis of which is transversely shiftable including, in combination, a finger movable in an endless path intersecting the disk adapted to feed said disk, and means adapted to alter the locus 30 of said path to one in which the finger fails to feed said disk.
34. Moving picture apparatus using a shiftable disk picture record including, in combination, two disk shifting worms, means for axially shifting one worm by 35 rotation of the other, a window at the optical axis of the apparatus, means adapted resiliently to press said disk against said window during disk shifting by one worm, and means adapted to relieve said pressure during disk shifting by the other worm.
35. Moving picture apparatus using a shiftable disk picture record including, in combination, two disk shifters, means adapted to rotate said disk, and means 40 adapted axially to shift one shifter in one direction by rotation of said disk, and means adapted axially to shift said shifter in the opposite direction by rotation of the other shifter.
36. Moving picture apparatus using a rotary disk picture record, the axis of which is transversely shiftable including, in combination, a driving shaft, a disk feeding finger reciprocal longitudinally and transversely of said disk, means adapted to shift the locus of the path of said finger to position where it fails operatively to engage said disk, a gear driven by said disk and shiftable therewith, and a worm rotated by said gear to shift said disk.
37. Moving picture apparatus using a rotary disk picture record, the axis of which is transversely shiftable including, in combination, a driving shaft, a disk feeding finger reciprocal longitudinally and transversely of said disk, means adapted to shift the locus of the path of said finger to position where it fails operatively to engage said disk, a gear driven by said disk and shiftable therewith, and a worm rotated by said gear to shift said disk, a second worm driven from said driving shaft without intermedia- 50 tion of said disk, and means adapted to connect said first mentioned worm for being 55 shifted by rotation of said second worm.
38. Moving picture apparatus using a rotary disk picture record, the axis of which is transversely shiftable including, in combination, a driving shaft, a disk feeding finger reciprocal longitudinally and transversely of said disk, means adapted to shift the locus of the path of said finger to position where it fails operatively to engage said disk, a gear driven by said disk and shiftable therewith, and a worm rotated by said gear to shift said disk, a second worm driven from said driving shaft without intermedia- 60 tion of said disk, and means adapted to connect said first mentioned worm for being 65 shifted by rotation of said second worm, a controller driven by operation of the apparatus, and a trip adapted to be moved by 70

said controller into and out of position to shift the locus of said finger.

39. Moving picture apparatus using a rotary disk picture record, the axis of which is transversely shiftable including, in combination, a driving shaft, a disk feeding finger reciprocal longitudinally and transversely of said disk, means adapted to shift the locus of the path of said finger to position where it fails operatively to engage said disk, a gear driven by said disk and shiftable therewith, and a worm rotated by said gear to shift said disk, a second worm driven from said driving shaft without intermedia-
15 tion of said disk, and means adapted to connect said first mentioned worm for being shifted by rotation of said second worm, a controller driven by operation of the apparatus, and a trip adapted to be moved by
20 said controller into and out of position to cause shifting of the locus of said finger, a spring adapted to cause pressure on the face of the disk adjacent the optical axis, and means actuated by said controller for reliev-
25 ing said pressure during disk shifting by said second worm.

40. Motion picture apparatus for exposing or projecting a disk record with spiral image

series comprising means for feeding the disk rotarily from image to image, a slow worm 30 turned by the disk, a fixed follower engaging the worm, a fast worm, a second follower engaging it and connected to shift the disk reversely, and a single means controlling both followers disengaging each when the 35 other is engaged, consisting of a rock shaft on which the followers are mounted, one fixed on the shaft the other relatively slide-
able along the shaft.

41. Motion picture apparatus for exposing 40 or projecting a disk record with spirally arranged feed perforations and a spiral image series including, in combination, means for operating said apparatus includ-
45 ing means for feeding the disk rotarily from image to image, comprising a reciprocatory feed finger engaging the feed perforations in the disk, an adjusting bar having pin and slot connection with said feed finger for finely adjusting said finger laterally to the 50 feed, an objective lens and means for finely adjusting the lens longitudinally to the feed.

In testimony whereof, I have affixed my signature hereto.

GIANNI BETTINI.
